(57) **CLAIM**

The ornamental design for a wall supported planter, as shown and described.

DESCRIPTION

FIG. 1 is a top, front, side perspective view of a wall supported planter embodying the present invention;

FIG. 2 is a bottom, front, opposite side perspective view thereof;

FIG. 3 is a front elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

The evenly-spaced broken lines illustrate environmental subject matter and the unevenly spaced broken lines illustrate breaks which indicate that the wall supported planter is of no particular width. None of the broken lines form any part of the claimed design.
